UNITED STATES PATENT OFFICE.

BENJAMIN LIPPER, OF PHILADELPHIA, PENNSYLVANIA, ASSIGNOR TO HIMSELF, AUGUSTUS A. LAZARUS, AND ISAAC A. SCHWARZ, ALL OF SAME PLACE.

DESIGN FOR A DRESS-TRIMMING.

SPECIFICATION forming part of Design No. 21,675, dated July 5, 1892.

Application filed June 8, 1892, Serial No. 435,988. Term of patent 3½ years.

To all whom it may concern:

Be it known that I, BENJAMIN LIPPER, a citizen of the United States, and a resident of Philadelphia, Pennsylvania, have invented a new and original Design for a Dress-Trimming, of which the following is a specification.

My design is fully shown in the accompanying drawings, in which—

Figure 1 represents a face view of a piece of the trimming, and Fig. 2 an edge view of the same.

The trimming has a central band *a*, composed of irregularly-disposed and overlapping loops, raised somewhat above the surface of the trimming, as shown in Fig. 2. On each

side of the central band is a border composed of loops *b b*, arranged in pairs, and within each pair of loops is a cord *d*, forming a serpentine figure. Extending longitudinally 20 along each border is a narrow band *f*.

I claim—

The design for a dress-trimming, substantially as described, and as shown in the accompanying drawings.

In testimony whereof I have signed my name to this specification in the presence of two subscribing witnesses.

BENJAMIN LIPPER.
